UNITED STATES PATENT OFFICE.

THOMAS A. MANNING AND ADOLPH A. ENGEL, OF MILWAUKEE, WISCONSIN.

BELT-RETAINING ATTACHMENT FOR TROUSERS.

Application filed May 31, 1921. Serial No. 473,732.

To all whom it may concern:

Be it known that we, THOMAS A. MANNING and ADOLPH A. ENGEL, citizens of the United States, residing at Milwaukee, county of Milwaukee, and State of Wisconsin, have invented new and useful Improvements in Belt-Retaining Attachments for Trousers, of which the following is a specification.

10 Our invention relates to improvements in belt holding clips for trouser waist bands.

The object of this invention is to provide a form of clip which can be expeditiously attached to trouser waist bands and clamped 15 in position thereon in such a manner as to provide openings, each of a definite size, to receive a belt, all of the openings being of uniform size.

More specifically our object is to provide 20 a staple shaped metal clip having barbs to be inserted through the waist band, and provided with means for limiting the extent to which the barbs may be passed through the waist band, whereby the outer member 25 of the clip may be spaced at a definite distance from the waist band, and a clinching point of definite length established for each barb.

Our invention contemplates the substitution 30 of metal clips for the strips of fabric heretofore stitched to the waist bands of trousers in a position to receive the belt, said metal clips being so constructed that a belt can be inserted through them with 35 greater facility than it can be inserted through any clips or loops of fabric heretofore used for a similar purpose. It is also our object to provide means for attaching 40 clips to trouser waist bands more expeditiously and with less expense than has heretofore been thought possible, our improved clip being less expensive in its assembled relation to the waist band than the fabric loops heretofore employed.

45 An embodiment of our invention is shown in the drawings, in which,

Figure 1 is a side elevation of our improved clip in assembled relation to a waist band and a belt, said band and belt being illustrated in cross section.

Figure 2 is a side elevation of the clip as it appears preparatory to its insertion in the

waist band, i. e., as it is commercially marketed.

Figure 3 is an end view, and

55

Figure 4 is a perspective.

Figure 5 is a perspective view of the blank from which the clip is struck up.

Like parts are identified by the same reference characters throughout the several views.

An elongated strip of metal, preferably formed of sheet steel cut into the form of a rectangular strip 1, as shown in Figure 5, is bent transversely along the dotted lines 2 65 to form elbows, as illustrated in the other views, the end portions having their extremities trimmed to form the pointed barbs 3. Between the point 3 and the elbow 2, the material composing the barb is partially 70 cut out and bent inwardly to form prongs 4 disposed at right angles to the barbs and parallel to the outer wall or back 5.

The clip formed as above described constitutes a staple shaped member, rectangular 75 in cross section, but differing from an ordinary staple by having the prongs 4 struck up from the legs of the barbs and projecting inwardly therefrom parallel to the wall 5. A staple of this kind can readily be pushed 80 through a piece of fabric, such as the waist band of a pair of trousers, until the prongs 4 contact with the waist band and limit the inward movement of the prongs. Thereupon the extremities 3 of the prongs may also be 85 bent inwardly and clinched upon the inner face of the waist band, as indicated in Figure 1, a portion of the fabric being clamped between the extremities 3 of the barbs and prongs 4. The outer wall or back 5 is thus 90 held at a definite distance from the waist band to which it is rigidly secured, and an opening of definite size provided through which the belt 7 may be looped, as clearly shown in Figure 1.

95

Inasmuch as the walls of the loop or belt receiving clip composing the loop will not collapse, it is possible to adjust the belt through them much more expeditiously than is the case where loops of fabric are employed. It is also possible to apply the clips to the waist band much more quickly than fabric loops can be stitched thereto, inasmuch as the staples can be driven into the

waist band either by hand or by machinery, and their movement into the band positively and definitely limited by the prongs 4.

We claim:—

- 5 The combination with the waist band of a pair of trousers, of a staple shaped clip having barbs extending through the waist band and clinched upon its inner surface, and also

having prongs projecting inwardly from the barbs and clinched upon the outer surface of the waist band, said band being clamped between the clinching members in a position to hold the back in a definite spaced relation to the band.

THOMAS A. MANNING.
ADOLPH A. ENGEL.
